United States Patent

Des. 237,770
Patented Nov. 25, 1975

237,770

PITCHER

Robert Daenen, Erembodegem, Belgium, assignor to Dart
Industries Inc., Los Angeles, Calif.

Filed Jan. 9, 1974, Ser. No. 432,024

Term of patent 14 years

Int. Cl. D7—01

U.S. Cl. D7—59

FIG. 2.

FIG. 1.

FIG. 4.

FIG. 3.

FIG. 6.

FIG. 5.

FIG. 1

FIG. 1 is a front elevational view of a pitcher showing my new design;

FIG. 2 is a side elevational view thereof;

FIG. 3 is a plan view thereof;

FIG. 4 is a bottom view thereof;

FIG. 5 is a cross-sectional view taken along line 5—5 of FIG. 3;

FIG. 6 is a front elevational view of a modified form of the pitcher of FIG. 1 wherein the lower portion is of greater depth; and

FIG. 7 is a side elevational view thereof.

I claim:

The ornamental design for a pitcher, substantially as shown and described.
